UNITED STATES PATENT OFFICE.

HUGO C. WELL, OF NEW YORK, N. Y., ASSIGNOR OF FIFTY ONE-HUNDREDTHS TO
FREDERICK A. B. MEINHARDT, OF NEW YORK, N. Y.

IGNITION SYSTEM FOR INTERNAL-COMBUSTION ENGINES.

1,167,456.

Specification of Letters Patent.

Patented Jan. 11, 1916.

Application filed August 27, 1914. Serial No. 858,806.

To all whom it may concern:

Be it known that I, HUGO C. WELL, a subject of the Emperor of Germany, and a resident of the city of New York, borough of the Bronx, county of Bronx, and State of New York, have invented a new and Improved Ignition System for Internal-Combustion Engines, of which the following is a full, clear, and exact description.

10 My invention has for its object to provide an ignition system for internal combustion engines, having a rotatable means for closing an open circuit connected with the spark plug of the engine.

15 Another object of the invention is to provide driving means for the rotatable means, which is operated by the piston rod of the engine.

Other objects of the invention will appear 20 in the following specification, in which the preferred form of my invention is disclosed.

In the drawings similar reference characters refer to similar parts in the two figures, in which—

25 Figure 1 is a sectional elevation of the invention showing my improvement, and Fig. 2 is a fragmentary sectional view showing the terminals of the circuit and the conducting member mounted on the sleeve for contacting with the terminals.

30 By referring to the drawings it will be seen that the engine cylinder 5 has a head 6 with a spark plug 7, and that within the cylinder 5 there is a sleeve which is provided with ports coöperating with ports 9, 35 10 and 11 in the cylinder 5. To the top of the sleeve 8 there is secured an insulating member 12 on which is mounted a spring contact member 13, this spring conducting member 13 being secured to the insulating member 12 by means of the pins 14. This resilient or spring conducting member 13 is provided for contacting with the terminals 15 on the pins 16 which are disposed in the 40 openings 17 which are made in the insulating members 18, the said insulating members 18 being disposed in the openings 19 in the cylinder head 6. The pins 16 have binding posts 20 to which the wires 21 and 22 are secured, these wires 21 and 22 forming part of the open circuit connected with the spark plug 7.

45 It will be understood that with the rotation of the sleeve 8 the resilient conducting member 13 will periodically engage the terminals 15.

minals 15 by closing the open circuit with which the spark plug is connected, a magneto or battery being included in the circuit, in the customary manner.

50 It will be seen by reference to Fig. 1 of the drawings, that the head 6 of the engine is disposed within the engine cylinder 5 and is spaced therefrom to form an annular guideway 23 in which the top of the sleeve 8 is disposed, the terminals 15 being disposed in this guideway 23 and the resilient conducting member 13 being also disposed for traveling in the said guideway.

55 There is a bevel gear 24 at the bottom of the sleeve 8 and meshing with this bevel gear 24 there is a bevel gear 25 rotatably mounted in the crank case 26 of the engine, a crank 27 being secured for rotating the said bevel gear 25 with an arm 28 of the crank 27 disposed in the slot 29 of a piston rod 30. The crank is prevented from slipping out 60 of the slot 29 by a flange 31 to which is secured the outer end of the arm 28. The springs 32 are provided for holding the arm 28 yieldingly in a predetermined position in the slot 29. The piston rod 30 is articulated at 33 to a piston 34, and the lower end of the piston rod 30 is articulated to a crank 35 on the engine shaft 36.

65 Having thus described my invention, what I claim as new and desire to secure by Letters Patent, is:

1. In an ignition system for internal combustion engines, a cylinder having a head and a spark plug, a sleeve rotatably mounted within the cylinder, a conducting member on the sleeve adjacent the head, an open circuit for the spark plug having terminals within the cylinder in the path of the conducting member, and means for rotating the sleeve.

70 2. In an ignition system for internal combustion engines, a cylinder having a spark plug, an open circuit for the spark plug, having terminals spaced apart within the cylinder, a sleeve rotatably disposed within the cylinder, a conducting member on the sleeve for periodically contacting with the terminals, and closing the circuit with the rotation of the sleeve, and means for rotating the sleeve.

75 3. In an ignition system for internal combustion engines, a cylinder having a spark plug, an open circuit for the spark plug and having terminals spaced apart within the

cylinder, a sleeve rotatably mounted within the cylinder and coaxially therewith, a conducting member on the sleeve for periodically engaging the terminals to close the circuit, a piston within the cylinder, a piston rod articulated to the piston, and means operable by the piston rod for rotating the sleeve.

4. In an ignition system for internal combustion engines, a cylinder having a head extending within the cylinder, with a portion of the head spaced from the cylinder to form an annular guideway, a spark plug in the head, an open circuit for the spark

plug and having terminals spaced apart 15 within the guideway, a sleeve rotatably mounted in the cylinder and having an end extending into the guideway, and a conducting member on the said end of the sleeve for periodically engaging the terminals to close 20 the circuit.

In testimony whereof I have signed my name to this specification in the presence of two subscribing witnesses.

HUGO C. WELL.
